UNITED STATES PATENT OFFICE.

RICHARD D. GALLAGHER, JR., OF NEW YORK, N. Y.

RAILWAY BUFFING MECHANISM.

1,301,423.

Specification of Letters Patent. Patented Apr. 22, 1919.

Application filed December 8, 1917. Serial No. 206,266.

To all whom it may concern:

Be it known that I, RICHARD D. GALLAGHER, Jr., a citizen of the United States, and resident of New York, in the county 5 and State of New York, have invented certain new and useful Improvements in Railway Buffing Mechanism; and I do hereby declare the following to be a full, clear, and exact description of the same, reference being had to the accompanying drawings, forming part of this specification.

Under modern traffic conditions it is often desirable and sometimes necessary to run certain classes of freight cars, particularly 15 refrigerator cars, in trains composed in part of passenger cars. Difficulty has been experienced in providing proper buffing mechanism with which the cars are adapted for either freight or passenger train service, 20 especially where they embody steel under-frames.

The object of the present invention is to provide a buffing mechanism embodying certain novel features of construction which 25 might be used in other car construction, but is especially designed for application to refrigerator cars having steel under-frames or under-frames wherein the neutral axis of the main steel sills is in a line below the 30 center line of buffer strain. Owing to this condition in the construction of cars of this type it has, in the present arrangement, been found most convenient and desirable to arrange the spring or yielding support of the 35 buffing mechanism back of the end sill of the car, instead of in front of the end sill, as has heretofore been proposed. In addition, it has been found desirable to provide a means whereby the buffer face plate may 40 be moved to occupy a normal position a greater or less distance from the end sill of the car, inasmuch as under certain conditions it must be held projected a considerable distance in order to properly coöperate with 45 the corresponding mechanism of the adjacent car, and under other conditions, or where the car is coupled, in a freight train for example, the buffer mechanism must be moved inwardly or backwardly to avoid interference with the coupler operating mechanism on the adjoining car.

All of these objects are attained in a simple and convenient structure, which, if desired, may be applied to existing cars without alteration in their frame and sill members, other than the formation of perfora-

tions in webs and flanges and the riveting of attachments thereto.

Referring to the accompanying drawings, 60

Figure 1 is a plan view, partly in section and partly broken away, of the essential members of one end of a car frame showing the application of the present invention thereto.

Fig. 2 is a section in a vertical plane indicated generally by the line 2—2 of Fig. 1, showing one of the buffer stems in elevation.

Fig. 3 is a transverse sectional elevation in the broken plane indicated by line 3—3 70 of Fig. 1.

Fig. 4 is a detail transverse section in a plane indicated by the line 4—4 of Fig. 1.

Fig. 5 is a sectional elevation on the line 5—5 of Fig. 1.

Fig. 6 is a detail section on the line 6—6 of Fig. 1.

Fig. 7 is a perspective view of the chafing plate shown in section in Fig. 6.

The parts of the under-frame of the car 80 illustrated embody the usual bolster plate A; main sills B, which may be of integral or built-up channel iron construction, as usual; and the draft members C, which in effect form extensions of the main sills B, 85 but have their upper edges above the level of said sills, their rear ends being of reduced width, so as to fit within and be riveted to the flanges of the main sills B. At their forward ends the draft members C are connected with and support the end sill D of the car, and between them is located the usual draft rigging, not shown herein further than to indicate in dotted lines the position of the coupler head and shank E. 95

For supporting and guiding the buffer stems F the end sill B is provided with reinforcing buffer stem sleeves d, the opening in one of said sleeves being enlarged laterally to afford considerable clearance for the buffer stem, as is common in this art, in order to permit the buffer face plate to assume an angular position with relation to the end sill, as will be presently apparent. Two buffer stems are preferably employed and their forwardly projecting ends are adapted to support the buffer face plate G preferably through connections whereby the normal position of the face plate may be fixed at a greater or less distance from the end 110 sills. In the preferred construction, the face plate is provided with rearwardly pro-

jecting buffer sleeves H into which the ends of the stems F project with sufficient clearance to permit of the necessary angular movement of the face plate in rounding 5 curves, etc., and the connections between the sleeves H and stems are formed by coupling pins h , conveniently held against loss by a flexible connection, and adapted to coöperate with suitable holes or openings in 10 the stems and with any one of a plurality of holes, such as indicated at h' in the buffer sleeves H. For preventing the complete detachment of the buffer head or face plate from the stems when the coupling pins h 15 are removed, the stems are conveniently provided with transverse retaining stops or pins h^2 which in assembling the parts may be inserted through transverse holes h^3 in the sleeves and rigidly fastened in place by 20 rivets h^4 inserted through the holes h' . The retaining pins h^2 coöperate with internal shoulders of the sleeves H to prevent the withdrawal of the sleeves but, at the same time, the endwise clearance is sufficient to 25 permit of the face plate and sleeves being moved inwardly or backwardly toward the end sill of the car a sufficient distance to permit of the coupling pins being located in the other holes adapted for their reception 30 and consequently the said face plate may be located normally in either position of its adjustment.

At their inner ends the buffer stems are adapted to coöperate through suitable yielding supports with back stops rigidly associated with the under-framing of the car, and the present invention contemplates the provision of a means for connecting these parts in such wise that the frame itself is 35 not weakened, but, on the contrary, additional strength and rigidity are imparted to it.

To accomplish these ends, there is preferably provided for each buffer stem, a Z- 40 bar or iron member I which, at its rear end, has its bottom flange riveted rigidly to the bolster plate A and at its forward end is rigidly connected with the draft members C by angle irons i and intermediate the 45 ends it is connected with both the draft members and top flanges of the main sills by angle irons i' .

The upper flanges or legs of the Z-bars are connected by a transverse plate K firmly 50 riveted thereto and projecting at each end beyond the webs of the Z-bars. The back stops proper, which are preferably in the 55 form of U-shaped forgings L have their upper legs firmly riveted to the ends of the transverse plate K and their lower legs firmly riveted to the bottom flanges of the Z-bars, as clearly indicated at l in Figs. 60 1 and 5.

The rear ends of the stems F pass through 65 openings in the back stops L and are pro-

vided with keys f to limit their forward movement, while their rearward movement is limited by mechanism to be presently described. The said rear ends of the stems F are preferably cylindrical and take their bearing in collars or washers M seating in the openings in the back stops and forming in effect not only bearings for the stems themselves, but seats for the rear ends of the springs which constitute the yielding 70 supports of the buffering mechanism. In the preferred construction, spring mechanism is employed which performs several important functions, namely, first, to provide for a comparatively easy yielding movement of 75 the buffer face plate up to that point where the coupling of the cars is effected, and from thence on, affording a heavy and rapidly increasing resistance to the inward or rearward movement of the buffer face 80 plate, in each instance provision being preferably made whereby the yielding movement will be arrested before the elastic limit of the spring has been reached or the coils have been set up solid. Conveniently, the 85 rear ends of the stems are provided with shoulders m , against which collars m' may seat, said collars m' serving as the seats for the forward ends of relatively light springs N. In rear of each light 90 spring N and separated from it by a second collar n is a relatively heavy spring N', the relation of the parts being such that the collar m' will contact with the collar n when further elastic movement of the light 95 spring N is to be arrested, and this position of the parts is such that the collars will contact at about the point where the coupling of the cars is effected. Thereafter, further inward movement of the face plate of the 100 buffer only operates to compress the heavy 105 buffer spring N'.

The buffer stem sleeves or reinforcing members d on the end sill D are subject to considerable wear from the movement of the buffer stems, this being particularly apparent on the bottom surfaces which support the weight of the stems and buffer face plate. To overcome this wear, it is preferred to form said sleeves or reinforced 110 members with an internal pocket or recess in the face adjacent the web of the end sills for the reception of a down-turned end p , Figs. 6 and 7, of a chafing plate P. With this construction, while the chafing plate is 115 loose to the extent that it may be readily inserted and removed when no buffer stem is present in the opening, it is nevertheless held firmly in place when such stem is present and will afford a good bearing and wearing surface with which the stem will 120 co-operate.

What is claimed is:

1. A buffer mechanism for railway cars embodying buffer stems, yielding supports 125

for holding the stems advanced, and a buffer face plate adjustably mounted on the projecting ends of the stems, whereby the face plate may be positioned normally a greater or less distance from the end sill of the car.

2. A buffer mechanism for railway cars embodying buffer stems, yielding supports for holding the stems advanced, a buffer face plate on the projecting ends of the stems and pivotal and adjustable connections between the face plate and the stems, whereby either end of the face plate may yield a greater distance than the other and the face plate may be normally positioned a greater or less distance from the end sill of the car.

3. A buffer mechanism for railway cars embodying buffer stems, yielding supports for holding the stems advanced, a buffer face plate having rearwardly projecting sleeves for coöperation with the stems, and means for adjustably connecting the sleeves and stems, whereby the face plate may be positioned normally a greater or less distance from the end sill of the car.

25 4. A buffer mechanism for railway cars embodying buffer stems, yielding supports for holding the stems advanced, a buffer face plate having rearwardly projecting sleeves for coöperation with the stems, adjustable connections between said stems and sleeves, embodying a plurality of openings and removable coupling pins and stop members for preventing the complete separation of said sleeves and stems when the pins are removed.

5. In a buffer mechanism for railway cars, the combination with a car frame embodying main sills, draft members, bolster plate and an end sill rigidly connected together, of buffer stems movably mounted in bear-

ings in the end sill and projecting into proximity to the bolster plate, back stops, and springs for supporting the buffer stems against inward movement, and back stop supports formed of members having flanges and rigidly united to the bolster plate, main sills and draft members of the car frame.

6. In a buffer mechanism for railway cars, the combination with a car frame embodying bolster plate, main sills, draft members and end sills rigidly connected together, of buffer stems mounted in bearings in the end sill, back stop supporting members rigidly connected with the bolster plate, main sills and draft member, a transverse plate connecting said back stop supporting members, back stops rigidly connected with said transverse plate and supporting members, and springs interposed between said back stops and stems for yieldingly resisting the inward movement of the latter.

7. In a buffer mechanism for railway cars, the combination with a car frame embodying a bolster plate, sills, draft members and end sills rigidly connected together, of Z-irons rigidly connected at their lower portions with the bolster plate, main sills and draft members, a transverse plate bridged between and rigidly connecting the top flanges of the Z-irons, back-stops bridged between and supported by the bottom flanges of the Z-irons and transverse plate, buffer stems mounted in bearings in the end sills and back stops respectively, and springs supported by said back stops for resisting the inward movement of the buffer stem.
